EDGING MACHINE

Samuel H. Coddington, Detroit, and Walter
Merry, River Rouge, Mich.

Application April 1, 1947, Serial No. 738,664

1 Claim. (Cl. 80—36)

1

This invention relates to an edging machine, and more particularly to a device for cleaning up the edges of a burred strip of steel or other material.

Heretofore strips of steel or other material after shearing or cutting, have a burr or other irregularity formed upon their longitudinal edges. Oftentimes the material is slightly twisted or has a camber therein.

It is the purpose and principal object of this invention to remove said burr and to also remove said camber.

It is the object of this invention to provide a machine having a plurality of dies through which the strip of material may be passed with the dies cooperatively engaging the opposite longitudinal edges of the material for removing the burr or other irregularities therein.

It is the further object of this invention to provide die means which tend to eliminate the camber of the material as well as adjustable rolls for pulling the material through the machine and also to cooperate in straightening out said material.

These and other objects will be seen from the following specification and claim in conjunction with the appended drawings in which:

Figure 1 is a plan view of the edging machine.

Figure 2 is a side elevational view thereof.

Figure 3 is a fragmentary section on line 3—3, Figure 1.

Figure 4 is a fragmentary section on line 4—4, Figure 1.

Figure 5 is a fragmentary section on line 5—5, Figure 1.

Figure 6 is a fragmentary section on line 6—6, Figure 5.

Figure 7 is a section on line 7—7, Figures 1 and 4.

Figure 8 is a section on line 8—8, Figure 1.

Figure 9 is a fragmentary enlarged section similar to Figure 8.

Figure 10 is an enlarged view on line 10—10 of Figure 8.

Figure 11 is an elevational section on line 11—11, Figure 1.

Figure 12 is a transverse section on line 12—12 of Figure 11.

Figure 13 is a fragmentary view on line 13—13, Figure 2.

Figure 14 is a section on line 14—14 of Figure 3.

It will be understood that the above drawings illustrate merely one preferable embodiment of the invention and that other embodiments are

2

contemplated within the scope of the claims hereafter set out.

Referring to the drawings, Figures 1 and 2, the edging machine consists of legs 11, platform 12, side members 13 and 14, and top members 15 and 16. A second platform 17 is provided in a lower parallel plane to tops 15 and 16; and spaced platforms 18 are also mounted above and in spaced relation to platform 12.

10 Electric motor 19, Figures 2 and 13, is mounted on platform 12 with its rotatable spindle 20 carrying pulleys 21 to effect movement of drive belts 22, which rotate pulleys 21' on shaft 24.

15 Journals 23, Figures 2 and 13, are mounted in spaced relation upon platforms 18 to rotatably support the outer ends of drive shaft 24. The latter rotatively projects through free-wheeling clutch housing 26 so that upon rotation of said shaft in one direction sprocket 25 is rotated in a corresponding direction. Said free-wheeling clutch is constructed so that rotation of shaft 24 in the opposite direction would effect no movement of sprocket 25.

20 In other words, sprocket 25 is actuated and rotated by shaft 24, yet said sprocket is free to rotate independent of shaft 24 as where said sprocket may be rotated faster than shaft 24 in the manner hereafter set out. Furthermore, rotation of shaft 24 in the opposite direction would affect no movement of said sprocket.

25 Shaft 24 thus turns sprocket 25 effecting movement of sprocket chain 28 in one direction transmitting rotative motion in one direction to shaft 29 through sprocket 30 thereon.

30 A reversing clutch mechanism 31 is keyed slidably upon shaft 24 for rotation therewith normally out of engagement with sprocket 27 loosely journaled on shaft 24. Lever 32 is pivotally supported at 34 at one end with its other end joined at 35 to the movable member 36 forming a part of solenoid 37.

35 The latter is mounted upon upright portion 38 of the device by bolts 39. Clutch 31 has an outwardly extending sleeve which projects around shaft 24 and has a pair of spaced collars 31' between which the central portion 32' of lever 32 projects.

40 When it is desired to reverse the operation of the device to back up the strip of material inserted therein for instance, motor 19 is manually reversed by a suitable switch not shown, and solenoid 37 is simultaneously energized. Shaft 24 will thus rotate in the opposite direction, and in view of the free wheeling clutch 26 rotates free 45 of sprocket 25. Member 36 of said solenoid moves

inwardly to engage the reversing clutch mechanism 31 with sprocket 27 to thereby drive the same in the reverse direction.

Chain 28' interconnects sprocket 27 and a corresponding sprocket 30' on shaft 29. Shaft 29 rotatably mounted within journal 40 on base 12 projects into gear box 41 to effect rotation in unison of shafts 42 and 43 which upwardly project therefrom and rotate as indicated in Figure 13.

Corresponding shafts 44 and 45 are joined to shafts 42 and 43 by universal couplings 46 whereby shafts 44 and 45 may be rotatively driven regardless of their adjustment transversely of shafts 42 and 43.

Referring to Figure 4, inwardly projecting L shaped channel members 47 project down from top members 15 and 16 to which they are secured as by welds 48. Spaced transverse supports 49, Figures 1 and 4, rest upon the lower portions of members 47, while their opposite ends are suitably secured to the under sides of members 13 and 14.

The central support 50 is intermediate supports 49 and is likewise secured at its ends to the undersides of members 13 and 14. Guide bars 51 are mounted along the outer edges of supports 49 and immovably retained thereon by bolts 52. Central guide bar 53 is centrally mounted upon support 50 and retained thereon by bolts 54.

As shown in Figures 1, 3 and 4, there are four die carrying blocks arranged in pairs 54 and 55, each pair being slidably mounted partially upon outer supports 49 and with their inner portions slidably mounted upon portions of central support 50.

Guide bars 51 and 53 bear against the side walls of blocks 54 and 55 to guide their in and out adjustments, and to retain said blocks against movement transverse to their supports 49 and 50.

Bolts 56 project down through corresponding openings in blocks 54 and 55 and are threaded into retaining plates 57 which slidably bear against the under sides of supports 49 and 50, and are intended to retain said blocks upon these supports.

As shown in Figures 1 and 3, each of the blocks 54 and 55 are interconnected at their outer ends by tie bars 58 and 59. Tie bars 58 and 59 are immovably joined to the set of blocks 54 by screws 60. However, the opposite ends of tie bars 58 and 59 are adjustably joined to the set of blocks 55 by screws 61 and the lock nuts 62. Thus blocks 55 may be adjusted in and out relative to blocks 54 and then set in any predetermined position. However, tie bars 58 and 59 are also manually adjustable in and out being threadably joined by hand screws 63. The outer ends of said screws project through plates 64 secured upon the outer sides of members 13 and 14 by screws 65, Figure 2.

Screws 63 carry calibrated collars 66 which bear against plates 64 and are adapted to indicate the in and out adjustment of blocks 54 and 55. Adjusting handles 67 are mounted on the outer ends of screws 63 so that on manual adjustment thereof blocks 54 and 55 may be moved in and out towards and away from each other, to accommodate the particular width of the stock sent through the edging machine.

Each of the two blocks 54 and the two blocks 55 have mounted thereon cover plates 68 secured in position by screws 69. Referring to Figure 3 block 54 is illustrated, being similar to the other

block 54 and the pair of oppositely arranged blocks 55.

It will be seen that block 54 is cut away at its top inner portion, while the bottom portion thereof projects inwardly and has a vertical opening therein within which are secured upright bearings 70. A corresponding bearing 71 is aligned therewith and secured within a corresponding recess formed in their inner portion of cover plate 68.

Rotatable shaft 44 thus projects up through and is journaled within bearings 70 and 71. And similarly, rotatable shaft 43, Figure 13. Cylindrical die blocks 72 are respectively mounted upon the upper ends of drive shafts 44 and 45 within their supporting blocks 54 and are rotatably secured upon said shafts by keys 73 thereon which project into corresponding recesses in said die blocks as illustrated in Figures 3 and 14.

Die blocks 72 mounted in spaced relation, Figure 1, have the central aligned annular concave recesses or dies 74 to cooperatively receive the opposite longitudinal edges of the strip of stock 75 from which it is sought to remove the burrs thereon.

As illustrated in Figure 1 there is a second set of cylindrical die blocks 76 which are also annularly grooved to cooperatively receive and bear against the longitudinal edges of the strip of stock 75. Said blocks 76 are respectively mounted within their pair of supporting blocks 55 and are idly journaled therein by suitable shafts 77 which are rotatably journaled and supported within bearings 70 and 71 mounted and assembled as in Figure 3.

Referring to Figures 1, 2, 5 and 6 it is seen that a pair of spaced L shaped stock receiving guides 78 are mounted upon top member 15 and adjustably secured thereon by bolts 79 which project therethrough and through transverse slots 80 formed in top member 15.

A second pair of spaced L shaped stock receiving guides 81 are mounted upon top member 16 and adjustably secured thereon by bolts 82 which project therethrough and through corresponding transverse slots 80 formed in top member 16.

Members 78 guide the stock into the annular recesses 74 of die blocks 72, while members 81 guide the stock after it leaves the corresponding recesses in die blocks 76 until the stock reaches the rolls hereafter described.

Guides 78 are bent angularly outwardly to form a receiving mouth 83 for the stock 75 as it is projected thereinto.

As shown in Figure 5 a pair of elongated stock hold-down guides 84 are vertically mounted against the inner walls of guides 78 and angularly adjusted and secured therein by bolts 85 which project therethrough and through vertical slots 86 formed in members 78. Bolts 85 may thus be raised or lowered within slots 86 and retained in the desired adjusted position against upward movement by set screws 87.

Normally stock hold-down guides 84 will be set to the downwardly inclined dotted line position shown in Figure 6 thereby facilitating the entry of stock 75 thereunder. The leading lower edges 88 of stock hold-down guides 84 are angularly inclined upwardly providing a stock receiving mouth 89 to guidingly receive the stock 75 directing the same to the undersides of members 84.

A pair of substantially triangle blocks 90 projected inwardly from the inner edge of top mem-

ber 15 provide an extension therefor to supportingly guide the stock towards the grooves 74 in rotatable die blocks 72. Blocks 90 are mounted upon the under sides of the horizontal legs of guide members 78 and are secured thereunder by screws 91.

Referring to Figures 7, 8, 9 and 10 the central cross support 50 has mounted thereon the pair of spaced supporting guides 92 upon which the stock 75 rides as it passes between die blocks 72 and 76. Guides 92 Figures 8 and 10 are mounted on member 50 for adjustment transverse to the movement of the stock for accommodating varying widths thereof. Guides 92 are adjustably held down by bolts 93 which project therethrough and through slots 94 formed in support 50.

Inverted L shaped stock hold-down members 95 are mounted over members 92 in inverted position, and slidably positioned thereon as illustrated in Figures 7, 8 and 9. Adjusting screws 96 are threaded down through hold-down members 95 to threadably engage stock supports and guides 92. Thus members 95 may be raised or lowered with respect to guides 92 merely by adjusting set screws 96. Once properly adjusted to the height of the stock contemplated, they may be locked in position by the screws 97 which interconnect members 95 and 92. To adjust members 95 screws 97 must be first loosened.

Referring to Figures 1, 2, 11 and 12, a set of rolls is mounted upon platform 17, which forms a part of the edging machine base, best illustrated in Figure 2. Said rolls have a rectangular support 98, positioned on platform 17 and secured thereon by bolts 99.

A pair of bottom roll supporting members 100 are mounted in spaced relation upon support 98 and are retained in position by the same bolts 99, Figure 11. Each of members 100 is positioned between the spaced uprights posts 101 which are respectively joined to members 100 by screws 102. As illustrated in Figures 1 and 11, the inner edges of members 101 are centrally slotted at 101' throughout their length to receive the central side projections 100' which form a part of members 100, and which project from opposite ends thereof.

Secondary upper adjustable roll supporting members 103 are positioned in spaced relation within uprights 101 and are vertically slidably therebetween. Spaced top cover plates 104 are positioned horizontally across the tops of the uprights 101 and secured thereto by screws 105. Members 103 also have central side projections 103' which are slidably positioned and retained within the inner longitudinal slots 101' formed within uprights 101. Plates 106 with central openings 107 are mounted upon the top of adjustable upper roll supports 103.

Said upper roll supports 103 are slidably adjustable vertically between uprights 101; and a plurality of coil springs 108 are interposed between roll supports 100 and 103 with their end portions respectively mounted within corresponding recesses 109 formed within said roll supporting members.

Upper roll supports 103 are thus resiliently mounted upon lower roll supports 100 which are normally in spaced relation being urged upwardly by springs 108. Cover plate 110 extends across uprights 101, bears against the under sides of members 104, and has a pair of spaced threaded openings aligned with openings 107 formed in plates 106.

Threaded adjusting means 111 project down

through corresponding openings in covers 104 threadably engaging plate 110 with their lower ends operatively projected down into openings 107 to bear against plates 106. Thus it is seen that downward adjustment of either or both screws 111 will effect downward movements of plates 106 and either or both of the upper roll supports 103 against the action of springs 108. Likewise, by raising screws 111, or either of them, either or both of said upper roll supports may be elevated under the expansive action of said springs.

Screws 111 which have a zero designating line 113 project up through stationary collars 112 upon which rotatable indicating members 114 are mounted. Members 114 calibrated at 115 are adapted for rotational adjustment lining up their zero designation with the lines 113 on screws 111, once the same have been manually set to properly level upper roll 126. Set screws 116 are threaded transversely through members 114 to frictionally bear upon screws 111 to lock members 114 in position. Now with members 114 movable with screws 111 it is possible to thereafter effect equal adjustments of the opposite ends of roll 126 by effecting equal adjustments of screws 111. Furthermore screws 111 may be separately adjusted and thereafter may still be returned to the initial zero position. Said screws have transverse slots 117 to facilitate manual adjustment thereof to raise or lower either or both of the upper roll supports 103. Hardened cylindrical roll 118 has a central supporting shaft 119 whose projecting ends are rotatably journaled within bearings 120 carried within lower roll supports 100. One end of shaft 119 projects through support 100 and carries gear 121 and sprocket gear 122, both being secured thereon by key 123. Outer sprocket gear 122 is interconnected with a drive sprocket 124, which is suitably keyed to drive shaft 24, by a sprocket chain 125.

Thus, motor 19, Figure 13, is adapted to also effect rotation of the lower roll 118 through pulley belts 22 and sprocket chain 125.

The upper adjustable cylindrical roll 126 has a central supporting shaft 127 whose projecting ends are rotatably journaled within bearings 128 carried within upper adjustable roll supports 103. One end of shaft 127 projects through support 103 and carries a gear 129 which is retained thereon by key 130, and which is the same size as gear 121 on lower roll shaft 119.

Gear 129 is at all times enmeshed with gear 121 so that rotation of shaft 119 effects a simultaneous rotation in the opposite direction of the upper roll 126. Operation of motor 19 will thus turn rolls 118 and 126 simultaneously in such manner as to draw the stock 75 therethrough, once the leading end thereof engages said rolls after passing between guides 81 shown in Figure 1.

The stock is normally mounted upon the edging machine or suitably supported adjacent thereto so that the leading end of said stock is projected on top member 15 for introduction into mouth 83 which forms a part of guides 78. The stock is manually or otherwise fed into mouth 83, Figure 6, below stock hold-down guides 84, and is suitably projected between guides 78, still bearing upon top member 15. It will be understood that stock hold-down members 84 also act as dies in levelling the stock and tending to eliminate any camber therein which might have resulted from the previous shearing or cutting operation. The stock then moves forwardly upon

inwardly projecting supporting extensions 90 illustrated in Figures 1 and 6 until the stock reaches inwardly turning die blocks 72.

Extensions 90 thus act as a supporting guide in directing the stock and its opposite longitudinal edges so that the same project into the annular concave slots 74 which form a part of die blocks 72. The stock is thus frictionally engaged by said blocks to further introduce the stock into the machine and to project it forwardly. Said annular recesses have the effect of putting a slight radius upon the top and bottom edges on each side of the stock at the same time flowing the metal sufficiently to eliminate any burrs from the longitudinal edges of the stock.

The stock leaves die blocks 72 and the recesses 74 formed therein, with the leading portion of said stock bearing upon guide blocks 92, Figure 7, and positioned below stock hold-down blocks or dies 95. Said guides 92 and 95 perform the very important function to keeping the stock straight and at the same time tending to eliminate any camber which may still exist in the stock. Said blocks function further to effectively retain the moving stock in a horizontal position so as to be properly introduced within the annular recesses 74 which form a part of the idle finishing die blocks 76. The stock is still moving in view of its frictional engagement with feeding die blocks 72.

The stock now moves forwardly between vertical guides 81 on top member 16 and is projected between rolls 118 and 126 to thereby complete the edging operation, and to roll out any irregularities which have formed in the stock due to the flow of metal during the edging operation. The rolls function further to maintain the stock in a horizontal position and to further prevent formation of any camber in the stock. Or, on the other hand, to eliminate any possible camber which may still exist.

It is important to note that sprocket gear 122 is smaller and has fewer teeth or sprockets than its driving gear 124 with the result that roll shaft 119 and the interconnected rolls 118 and 126 rotate faster than drive shaft 24 and the two die block rotating shafts 42 and 43.

Consequently, as soon as the leading portion of the stock 75 is frictionally engaged between rolls 118 and 126 it is seen that its longitudinal movement is speeded up. Thus, the stock is now driving the die blocks 72 in view of its frictional engagement therebetween. Shafts 44 and 45 are speeded up and likewise interconnected drive shafts 42 and 43.

It follows also that shaft 29 from gear box 41 is speeded up with result that temporarily sprocket gears 30 and 25 are rotated faster than drive shaft 24. In view of the free wheeling clutch connection between shaft 24 and sprocket 25 it is seen that this speedup of sprocket 25 is quite possible inasmuch as said sprocket is free to move independent of shaft 24. Naturally, as soon as the stock leaves die blocks 72 it is seen that said blocks will slow down to their normal driven speed through their connection with drive shaft 24.

Under certain conditions it is desirable to effect vertical adjustments of the stock supporting delivery table 16 shown in Figures 1 and 2. It has been found that under certain conditions a slight camber in the stock can be eliminated either by raising or lowering table 16 by the adjusting means 131 which interconnect said table and its supports 13 and 14. Thus the stock after leaving die blocks 76 may be raised or lowered

slightly as it is guided into horizontal rolls 118, 126.

After stock has had a shearing operation its edges on opposite sides thereof are differently formed, both being irregular, i. e. one side has a 90 degree edge with a burr, while the other side has a chamfer and is otherwise irregular.

After stock has had a slitting operation both of the opposite sides thereof are cut at substantially 90 degrees, and both have a burr formed along the same corresponding lower corners. The edging machine described hereinabove is universal in its function to produce a finished stock whose edges will have a radius or other shape corresponding to the shape of the die recesses in the rotatable die blocks employed. In any event all irregularities in the longitudinal edges of the stock are eliminated regardless of whether the same is initially sheared or slit.

Die blocks 72 and 76 shown in the drawings have a substantially concave annular recess formed therein which is curved, and which is adapted to put a radius along the opposite corners at each edge of the strip stock corresponding substantially to the shape of said recesses.

It is naturally contemplated that the edging machine be equipped with a plurality of interchangeable die blocks similar to blocks 72 and 76, but with different sizes of annular recesses depending on the gage of the stock, and also differently shaped recesses depending on the type of edge desired in the finished stock.

As illustrated in the drawings it is seen that the die blocks are easily removable from their supporting shafts and may be replaced or interchanged as and when desired.

Under some conditions it may be desired to round the opposite edges of the stock entirely, or to at least form an arc therein. The shape will depend entirely upon the shape of the recesses formed within a particular die block.

It is also contemplated that the edging machine will finish stock eliminating burrs and camber and end up with 90 degree edges. In this instance it is necessary that the recesses 74 in the die blocks be substantially rectangular in cross-section. In fact it is contemplated that the shape or cross-section of the annular recess could be varied considerably from angular, square, to arcuate depending upon the requirements of the finished products.

Having described our invention, reference should now be had to the claim which follows for determining the scope thereof.

55 We claim:

In an edging machine, a rotatable drive shaft, a gear box, a driving shaft operatively projected into said gear box, a sprocket gear secured on said driving shaft, a sprocket gear interconnected with said first sprocket gear and loosely journaled on said drive shaft, a free wheeling clutch on said drive shaft and engageable with said second sprocket for driving the same in one direction, a pair of spaced oppositely rotatable shafts operatively projecting from said gear box, a pair of rotatable die blocks mounted upon said shafts and having aligned annular concave recesses formed therein to operatively receive and forcefully bear upon the opposite longitudinal edges of a strip of stock as they draw the same therethrough at a predetermined rate of movement, a pair of interconnected oppositely rotatable vertically spaced rolls adapted to receive and compressively engage therebetween said stock after it passes said die blocks, a second sprocket on said drive shaft ro-

tatable therewith, a third sprocket gear joined to said rolls and having less teeth than said second gear, and a sprocket chain connecting said second and third gears interconnecting said drive shaft and said rolls to draw the stock through the machine at an increased rate of movement with the stock driving said die blocks at an increased rate of movement.

SAMUEL H. CODDINGTON.
